CARD PUNCHING MACHINE

Philip J. Williams, Bridgeport, Conn., and Robert H. Van Valkinburgh, Ambler, Pa., assignors to Sperry Rand Corporation, New York, N.Y., a corporation of Delaware

Filed May 21, 1962, Ser. No. 70,225

Term of patent 14 years

(Cl. D26—5)

FIG. 1 is a front and left-side perspective view of a card punching machine embodying our new design;

FIG. 2 is a plan view of the machine;

FIG. 3 is a rear and right-side perspective view of said machine.

We claim:

The ornamental design for a card punching machine, as shown.
